UNITED STATES PATENT OFFICE.

JOHN E. HENES, ALFRED A. HENES, AND ANTON NELSON, OF MENOMINEE, MICHIGAN,
ASSIGNORS TO HENES AND KELLER COMPANY, OF MENOMINEE, MICHIGAN, A CO-
PARTNERSHIP COMPOSED OF JOHN HENES, JOHN E. HENES, AND ALFRED A. HENES.

AUTOMATIC CLAMPING MECHANISM FOR BOTTLE-FILLING MACHINES.

1,321,916.

Specification of Letters Patent. Patented Nov. 18, 1919.

Application filed February 7, 1917. Serial No. 147,042.

To all whom it may concern:

Be it known that we, JOHN E. HENES, ALFRED A. HENES, and ANTON NELSON, citizens of the United States, residing at Menominee, in the county of Menominee and State of Michigan, have invented certain new and useful Improvements in Automatic Clamping Mechanism for Bottle-Filling Machines and the like, of which the following is a specification, reference being had to the accompanying drawings, forming a part thereof.

This invention relates to automatic clamping mechanism for bottle filling machines and the like, and the objects of the invention are to provide a simple and reliable mechanism for automatically clamping objects such as bottles when being filled on bottle filling machines, for example.

For the sake of simplicity and clearness of illustration and description, the invention is illustrated as applied to, and combined with, a bottle filling machine, but it is not intended by such illustration, and the description contained in this specification, to limit the use of the invention to bottle filling machines.

Referring to the drawings which accompany this specification and form a part thereof, which drawings illustrate an embodiment of this invention, and on which drawings the same reference characters are used to designate the same parts wherever they may appear in each of the several views, Figure 1 is a vertical section through a bottle filling machine, some parts being broken away; Fig. 2 is a horizontal section taken on the line 2-2, on Fig. 1 looking in the direction indicated by the arrows, parts being broken away; Fig. 3 is an elevation of a part of the machine; Fig. 4 is a vertical section on the line 4-4, on Fig. 1, looking in the direction indicated by the arrows, and Fig. 5 is a vertical section on the line 5-5 on Fig. 4 looking in the direction indicated by the arrows.

Referring to the drawings the reference numeral 1 designates a base ring, 2 a standard and 3 a sleeve which is secured to and supported by the standard. A yoke 4 is secured to the standard 2 and is provided with bearings for a driving shaft, 5 having a worm 6. The worm 6 meshes with a worm gear 7 secured upon a rotatable pipe 8 lo-

cated within the sleeve 3. A spider 9 is secured to the pipe 8 so as to rotate therewith and the spider 9 supports the pipe 8 and the revoluble parts of the machine by bearing upon the antifriction devices 10 which are located between race members 11 and 12, as will be readily understood from an inspection of Fig. 1 of the drawings. A tank 13 is secured to the upper end of the pipe 8 and a liquid pipe 14 is located inside of the pipe 8 and communicates with the interior of the tank 13 to supply the liquid to the tank for filling bottles. A compressed air pipe 15 also communicates with the interior of the tank 13 to deliver air under pressure into the tank above the liquid therein, when the liquid is charged with gas, in order to prevent the escape of gas from the liquid in the well-known manner. The tank 13 contains the float 16. The yoke 4 is provided with a downwardly projecting guide or bearing 17 for the lower end of the rotatable pipe 8, and is also provided with a reduced extension 18 which forms a liquid tight bearing or guide for the liquid pipe 14. A cap 19 is screwed onto this extension and forms an air tight 75 guide or bearing for the compressed air pipe 15. This construction is such that, while the yoke 4 and the cap 19 remain fixed, the rotatable pipe 8, the liquid pipe 14 and the compressed air pipe 15 are freely rotatable. 85 Liquid is supplied to the liquid pipe 14 and the tank 13 through the pipe 20 and compressed air, or any other suitable gas or gases, is supplied to the pipe 15 and the tank 13 by the pipe 21. The pipe 15 extends up 90 into the top of the tank 13 and the escape of compressed air from the pipe 15 into the tank is controlled by a valve 22. The float 16 is provided with a sleeve 23, which surrounds the pipe 15 and serves as a guide for 95 the float and compressed air is admitted from the compressed air pipe 15 into the tank 13 when the valve 22 is lifted by the sleeve 23, as the float 16 rises. The float 16 is hollow and an open-ended pipe 24 which 100 projects above the level of the liquid in the tank affords communication between the interior of the float and the interior of the tank 13 so that the air pressure is the same on the inside of the float and on the outside 105 thereof. The cover 25 of the tank 13 is provided with an air vent 26, the outlet of which is controlled by a cock 27 so that the rapidity

of the escape of the compressed air from the interior of the tank may be adjusted to suit working conditions. A valve 28 controls the escape of the compressed air from the interior of the tank 13 through the air vent 26 and the cock 27 and is controlled in its movements by the lever 29 which engages with the top of the sleeve 23, the construction and arrangement being such that when air is to be discharged from the tank 13 the valve 22 is closed to prevent the admission of compressed air into the tank and the valve 28 is opened to permit the escape of the compressed air from the tank so that liquid can flow into the tank through the pipes 20 and 14 to maintain a substantially uniform level of liquid in the tank. The tank 13 is provided with a plurality of filling heads 30, siphons, and sealing heads or abutment members 31. The siphons are composed of pipes 32 and 33, which screw into screw threaded communicating bores in the supporting and guide blocks 34. The sealing heads 31 are secured to the supporting and guide blocks 34 and are provided with packing 35 to make air tight seals for the necks of bottles. Air ducts 36 through the supporting and guide blocks 34 permit air to enter the bottles from the tank 13 to establish the same air pressure in the bottles as the air pressure which exists in the tank 13 or to permit the air to escape from the bottles into the tank 13 as the bottles are filled with the liquid. The communication between the interior of the tank 13 and the air ducts 36 is controlled by valves 37 which are raised from their seats by levers 38 when the supporting and guide blocks 34 are raised by bottles being clamped against the sealing heads 31. Springs 39 retain the supporting and guide blocks 34 in their lowermost positions except when raised by bottles as just described. Liquid valves 40 prevent the flow of liquid from the tank 13 through the siphons except at such times as the supporting and guide blocks 34 and the tubes carried thereby are raised and after the air pressure in the bottles has been substantially equalized with the air pressure in the tank 13. Valves 41 are provided to let the air escape from the bottles and thereby reduce the air pressure in a bottle to reestablish the columns of liquid in a siphon if, by any means, a siphon liquid column has ceased to exist. The machine is provided with centering guides 42 which are swung up to clear the bottles by a cam member 43 adjacent to the discharge chute 44 by which the bottles are automatically removed from the machine. The bottles are supported upon bottle rests or jaw members 45 which are capable of being moved automatically so as to clamp the bottles against the sealing heads or abutment members 31. The jaw members 45 are secured to rods 46 which are guided

by nut members 47 and cross heads 48. The spider 9 is illustrated as provided with a peripheral ring 49 which is pierced with apertures 50. Guide rods 51 depend from the peripheral ring 49 and are united at their lower ends by tie bars 52. The cross heads 48 are provided with antifriction rollers 53 to engage with the cam member 54 to depress the bottle rests or jaw members 45, or move them away from the sealing heads or abutment members 31. Flanged, screw-threaded bushings 55 pass through the apertures 50, screw into the nut members 47 and clamp brackets 56 securely to the peripheral ring 49. Each of these brackets 56 has a depending ear 57 on one side and a separable fixed plate provided with a depending ear 58 on the other side, and these ears support shafts 59 which are secured against rotation in any suitable manner as, for example, by set screws 60. Pulley wheels 61 are revolvably mounted upon the shafts 59 and are provided with grooves 62, ratchet teeth 63 and central cavities 64, in which are casings 65 containing springs 66. The casings 65 are keyed to the pulley wheels 61 by keys 67. The springs 66 are an ordinary form of spiral springs, such as are used for clocks and spring motors, and one end of a spring is secured to a shaft 59 by a screw 68, while the other end of the spring is secured to a casing 65 by a rivet 69. As the shafts 59 are fixed against rotation, rotation of the pulley wheels 61 in one direction winds up the springs 66 and the springs 66 can rotate the pulley wheels 61 in the opposite direction against any resistance less than the power exerted by the springs. Flexible members 70 are fastened to the pulley wheels 61 and to the cross heads 48 and, before these flexible members are fastened to the cross heads 48, the springs 66 are put under sufficient tension to raise the cross heads 48, the rods 46, the bottle rests or jaw members 45, and the bottles up into engagement with the sealing heads or abutments 31 and to continue the upward movement until the sealing heads or abutments are stopped by the filling heads 30. In order that filled bottles may be removed from the machine and empty bottles placed on the machine to be filled, the bottles, the bottle rests or jaw members 45, the rods 46, the cross heads 48 and the flexible members 70 are pulled down during the rotation of the rotatable parts of the machine by the antifriction rollers 53 engaging against the cam face 71 of the cam member 54, and these parts are held down for the requisite length of time by the antifriction rollers 53 running along under the horizontal part 72 of the cam member 54. When the antifriction rollers 53 strike against the cam face 71 of the cam member 54, which is stationary, and are forced downward there-

by, the springs 66 are wound up or put under tension, so that, as the antifriction rollers 53 ride out from under the horizontal part 72 of the cam member 54, the 5 springs 66 will unwind and elevate the bottles, the bottle rests or jaw members 45, the rods 46 and the cross heads 48, in a manner which will be readily understood. The cam face 73 of the cam member 54 prevents 10 the bottles from being moved suddenly up into contact with the sealing heads or abutment members 31.

Rocker arms 74 are loosely mounted upon the shafts 59 outside of the ears 57 and arms 15 75 are secured thereto and are loosely mounted on the other ends of the shafts 59 outside of the ears 58. The rocker arms 74 carry ratchet members 76 which are movable longitudinally of said rocker arms and 20 which are provided with ratchet teeth to engage with the ratchet teeth 63 on the pulley wheels 61. Springs 77 normally keep the ratchet members 76 in such positions that their ratchet teeth engage with the 25 ratchet teeth 63 of the pulley wheels 61, but the ratchet members 76 are formed with depending lugs 78 which carry antifriction rollers 79 which engage behind a releasing member 80, provided with cam ends 81 and 30 82, during a part of the rotation of the machine corresponding generally to the part of the rotation of the machine during which the antifriction rollers 53 are passing under the cam member 54. The releasing member 35 80 is so placed that it pulls the ratchet members 76 back against the tension of the springs 77 far enough so that the ratchet teeth on the ratchet members are freed from engagement with the ratchet teeth 63 on the 40 pulley wheels 61. The cam end 81 of the releasing member 80 should engage the antifriction rollers 79 and disengage the ratchet members 76 from the ratchet teeth of the pulley wheels 61 before the antifriction roller 45 53 of a particular clamping unit engages with the cam member 54. Rods 83 provided with heads 84 pass through holes in brackets 56 and are pivoted to the rocker arms 74. Parts of these rods are screw threaded and 50 55 are provided with nuts 85 so that springs 86, which surround the rods 83 and are held between the brackets 56 and the nuts 85, can be adjusted to the required tension for the clamping effort required. It will be apparent from an inspection of the construction shown on the right hand side of Fig. 1 of the drawings that the springs 86, which are of the open or compression type, tend to force the rocker arms 74 away from the 60 65 brackets 56 and in so doing exert a powerful upward tension on the flexible members 70, because the rocker arms 74 are locked to the pulley wheels 61 by the ratchet teeth on the ratchet members 76 engaging with the ratchet teeth 63 on the pulley wheels 61. The

springs 86 can be made short and very powerful in this mechanism because these springs are only relied upon to secure the final clamping effect desired, as the range of preliminary clamping movement desired 70 is obtained by the comparatively light springs 66.

The rocker arms 74 are provided with antifriction rollers 87 to roll up on a track 88 provided with the cam ends 89 and 90 to 75 compress the springs 86 by a sufficient amount to provide for the clamping action of these springs. The lifting of the rocker arms 74, or the compression of the springs 86, when the antifriction rollers 86 roll up 80 on track 88, also diminishes the friction between the ratchet teeth on the ratchet members 76 and the ratchet teeth on the pulley wheels 61.

The operation of the bottle filling mechanism is briefly as follows. Liquid such as beer, for example, is supplied to the tank 13 through the pipe 20 and the liquid pipe 14, and the level or height of the beer in tank 13 is maintained substantially constant by 85 the action of the float 16 in allowing the escape of compressed air by the valve 28 and in admitting compressed air by the valve 22. As bottles are lifted into contact with the 90 sealing heads or abutment members 31, these 95 sealing heads and the supporting and guide blocks 34, and pipes 32 and 33 carried thereby, are raised until the sealing heads are stopped by the filling heads 30, the valves 37 are opened to equalize the air pressures 100 in the bottles and in the tank 13, and the liquid valves 40 open permitting the beer to siphon from the tank 13 into the bottles.

The bottle filling mechanism forms no part of this invention and for a more complete 105 description of the construction and operation of the bottle filling mechanism reference may be had to United States Letters Patent, No. 1,166,520, granted January 4, 1916.

The operation of the clamping mechanism is as follows. Assuming that a bottle is firmly clamped by the spring 86 between the sealing head or abutment member 31 and the bottle rest or jaw member 45, as 115 shown on the right hand side of Fig. 1 of the drawings and that the revolving parts of the machine are revolving in the direction shown by the arrow on Fig. 2 of the drawings then, when an antifriction roller 87 strikes the cam end 89 of the track 88, the antifriction roller will ride up on the track 88, thereby elevating the rocker arm 74 and compressing the spring 86. It will be noted from an inspection of Fig. 2 of 120 the drawings that the releasing member 80 is shorter than the track 88. When the antifriction roller 87 has mounted the cam end 89 and is on the track 88, the antifriction roller 79 engages with the cam end 125 130 81

of the releasing member 80 and is moved backward carrying with it the ratchet member 76 against the tension of the spring 77 and releasing the ratchet teeth of the ratchet member 76 from the ratchet teeth of the pulley wheel 61. The spring 66 now keeps the bottle rest or jaw member 45, and the bottle in their elevated positions until the antifriction roller 53 strikes against the 10 cam face 71 of the cam member 54, and is forced down under the same, at which time the cross head 48, the rod 46, the bottle rest or jaw member 45, and the bottle are lowered or removed from the sealing head or 15 abutment member 31. During this movement the spring 66 is wound up and the spring 39 forces the supporting and guide block 34 down with the parts connected therewith. The bottle rest or jaw member 45 remains in its lowermost position as 20 long as the antifriction roller 53 is traveling under the horizontal part 72 of the cam member 54, so that ample time is afforded for removing the filled bottle from the bottle rest or jaw member 45 and placing 25 an empty bottle thereon. When the antifriction roller 53 rolls out from under the horizontal part 72 of the cam member 54, the spring 66 immediately commences to unwind and lift the cross head 48, the rod 46, the 30 bottle rest or jaw member 45 and the bottle, as fast as permitted by the cam face 73 of the cam member 54, until the neck of the bottle contacts with the sealing head 31, when the supporting and guide block 34 and the pipes 32 and 33 connected therewith are also lifted until the sealing head or 35 abutment member contacts with the filling head 30. At this time the antifriction roller 40 79 reaches the end of the releasing member 80 and runs off over the cam end 82 thereof permitting the spring 77 to move the ratchet member 76 so that its teeth engage with the ratchet teeth of the pulley wheel 61. Immediately thereafter the antifriction roller 45 87 runs off the cam end 90 of the track 88 and the spring 86 is permitted to expand and rock the pulley wheel 61 to exert the required tension upon the flexible member 50 70 to clamp the bottle firmly between the bottle rest or jaw member 45 and the sealing head or abutment member 31.

What is claimed is:

1. The combination with an abutment member of a movable jaw member, means 55 tending to move the movable jaw member toward the abutment member at all times, supplemental means of greater power to tend to move the movable jaw member toward the abutment member, and means to disconnect 60 said supplemental means from the movable jaw member.

2. The combination with an abutment member of a movable jaw member, means tending to move the movable jaw member 65 toward the abutment member at all times, means to move the movable jaw member away from the abutment member, supplemental means of greater power to tend to move the movable jaw member toward the 70 abutment member, and means to disconnect said supplemental means from the movable jaw member.

3. The combination with an abutment member of a movable jaw member, a spring 75 connected with said jaw member for moving said jaw member toward said abutment member, a cam for moving said jaw member away from said abutment member against the tension of said spring, a second spring 80 for forcing said jaw member toward said abutment member, and means for releasing said jaw member from the action of said second spring.

4. The combination with a jaw member 85 and an abutment member, which are both movable while maintaining their relative positions with respect to each other, of a spring for moving the jaw member toward the abutment member, a cam member for moving 90 the jaw member away from the abutment member against the tension of said spring, a fixed releasing member and a fixed track, a second spring for firmly clamping an object between the jaw member and the abutment member and means coöperating with said releasing member and said track for relieving said jaw member from the tension of said second spring.

In witness whereof we hereto affix our 100 signatures.

JNO. E. HENES.
ALFRED A. HENES.
ANTON NELSON.
